ABSTRACT OF THE DISCLOSURE

Stencil printing of a normally solid, heat fluidizable substance using hot air conducted onto the substance on the stencil to fluidize it and allow it to be squeegeed through the stencil, and then cooling to solidify it; the hot air being passed through swinging conduits movable with the stencil through a manifold to the stencil area.

This invention relates to stencil printing apparatus and methods utilizing printing materials that are normally solid at room temperatures, and more particularly relates to a method and apparatus for stencil printing with a solvent-free substance of 100% solids.

Most printing, including stencil printing, is conventionally practiced by employing a fluid ink of a finely divided coloring agent in a liquid solvent or carrier. By "printing" is meant the broad concept of applying an agent on a surface to form words, designs, colors, etc. This is normally done on a sheet and therefore will be described with respect thereto. As is known, freshly printed sheets require a substantial time for drying by evaporation of the carrier. The printed sheets must be kept separate during the drying process until drying is complete, to prevent offsetting or smearing. This necessitates large, expensive dryers which require a great deal of space. The dryer must be constantly driven to circulate the sheets. They must be supplied with substantial amounts of heat. Further, the freshly printed sheets cannot be handled for a substantial period after printing is complete.

It is an object of this invention to provide a method and apparatus of printing with a normally solid printing agent, without a liquid solvent or carrier, to effect printed sheets which are dry practically instantly when emitted from the printer.

Another object of this invention is to provide a practical method and apparatus of printing with a 100% solid type printing substance by the employment of heat in a manner to achieve high speed, controlled printing without overheating and scorching of any sheet portions, with uniform ink fluidization.

Another object of this invention is to provide a stencil printing unit that can employ the basic portions of a conventional stencil printer, yet usefully employ a normally solid type printing agent in a manner enabling high production output without any drying oven, recirculator or other drying facilities.

These and several other objects of this invention will become apparent upon studying the following specification in conjunction with the drawings in which:

FIG. 1 is a top plan view of the novel apparatus;

FIG. 2 is a side elevational view of the apparatus in FIG. 1;

FIG. 3 is an end elevational view of the apparatus;

FIG. 4 is an enlarged fragmentary sectional view taken on plane IV—IV of FIG. 1; and

FIG. 5 is an enlarged fragmentary sectional view taken on plane V—V of FIG. 1.

Referring now specifically to the drawings, the complete printing assembly 10 there illustrated includes a

2

basic stencil printing subassembly 12 and a recirculating hot air supplying subassembly 14.

Stencil printing subassembly 12 includes a conventional support framework 16 to be mounted on a floor surface, and supporting therein a shiftable stencil holder 18, a rotationally mounted, paper sheet clamping impression cylinder 20 suspended transversely in the center of the frame for cooperation with the stencil on stencil holder 18, and a conventional transverse squeegee apparatus 22 axially along cylinder 20.

The details of the impression cylinder 20 and its drive mechanism are preferably like that shown in U.S. Patent No. 3,120,180 assigned to the assignee herein. Likewise the details of the squeegee assembly are not critical, and may be like that shown in the noted patent, for example, or the equivalent.

Suitable drive mechanism (not shown), for example, like that in the above noted patent, may be provided to revolve impression cylinder 20. Each sheet to be printed is clamped in conventional clamp mechanism 20' of this cylinder, and subsequently released after printing. Stencil holder 18 is reciprocated back and forth over the length of the machine during rotation of cylinder 20. This may be done, for example, by having underside gear racks 18a and 18b meshed with spur gears 30a and 30b mounted on the rotational shaft (FIG. 3) of compression cylinder 20 to rotate therewith. Hence, the stencil support 18 is reciprocated between its dotted line position (FIG. 2) at one end of the bed, and its phantom line position (FIG. 2) at the opposite end of the bed. In so doing, it passes the stencil over progressive portions of a sheet pulled around revolving cylinder 20, to thereby print the sheet when ink is squeegeed through the stencil. The sheet is then discharged on to a suitable support 36 where it can be removed.

According to the concept herein, normally solid printing agents are used. Heat is applied to temporarily fluidize them. Specifically, preheated recirculated air is ejected in a pattern onto the stencil holder from its periphery. This is done to enable normally 100% solid, nonsolvent, printing or coloring agents to be squeegeed through the orifices of the stencil onto the sheet. The solid ink, normally in a powdered form, may be applied to the stencil by any suitable distributor, as by being ejected from a portion of the squeegee holder 22.

The heated air is provided using recirculating subassembly 14. This subassembly is preferably mounted above the stencil printing apparatus by a plurality of four corner support legs 34a, 34b, 34c and 34d. Mounted on the upper portions of these legs, spaced above the stencil printing subassembly is a thermally insulated plenum housing 36 forming a hollow internal chamber 36'. Suspended beneath this plenum chamber is a downwardly, outwardly flared warm air collection hood 38. Mounted along one side of housing 36 is a burner heater unit 40 which preferably employs combustible gas for a heat source. This discharges into a heater spiral 42 which receives dynamically flowing pressurized air through a duct 44 from a blower 46. Blower 46 is a centrifugal type, driven by electrical motor 48 through shaft 49, belt 51, and shaft 50. Shaft 50 is mounted on suitable bearing pillow blocks 52 and 52a. Motor 48 is mounted on a base 56, and blower 46, with its shaft, is mounted on a support 58. Both base 56 and support 58 are secured to a transverse beam 60 connected between legs 34c and 34d.

Air is propelled by blower 46 through duct 44 into heater spiral 42, and heated by combustion products from heater 40 ejected through outlet 64 into plenum chamber 36'.

The heated flowing air is conducted from this plenum chamber to the stencil area by downwardly depending

swinging tubular conduits, shown to be six in number. These conduits, namely 70a, 70b, 70c, 72a, 72b, 72c are open on the upper end into plenum chamber 36'. The lower ends are open to communicate to portions of a rectangularly shaped orificed hot air manifold 78. These ducts are arranged in a parallelogram and mounted with upper and lower swivel joints to swing arcuately with horizontal reciprocation of stencil holder 18. Each of the tubular ducts is formed of two telescopically interfitted members to automatically vary in length as the tubes oscillate arcuately between the solid line position and the phantom line position shown in FIGS. 1 and 2.

The swivel connections may take any of a variety of different forms, with one upper end swivel connection being shown in FIG. 4, and one lower end swivel connection being shown in FIG. 5. Referring to FIG. 4, tubular member 72a includes a hollow ball member 80a on its upper end, received in orificed socket member 36a formed in the plenum chamber 36 and through its insulation 37. Corresponding orificed joints 80b, 80c, 81a, 20 81b and 81c are provided for the other five telescopic conduits (FIG. 1).

The lower end of this member shown in FIG. 5 includes an interfitting telescoping member 72aa having a ball joint member 82a on its lower end, fitted within hollow socket member 84a which is in direct communication with the rectangularly configurated, tubular manifold 78.

This tubular manifold has outlet orifices 90 or the equivalent all around the inner peripheral portion thereof to eject the heated gases across the stencil surface throughout the entire area within the peripheral stencil support 18. The hot air therefore flows over the stencil S retained in this stencil support during the entire reciprocation of the stencil support. Hence, the hot air heats the solid coloring agent applied to the stencil and fluidizes it to enable the squeegee assembly 22 to force the fluidized material through the stencil on to the underlying surface, e.g., of a stock of sheets being advanced by impression cylinder 20. Immediately after the sheet is printed and ejected on discharge surface 36, it cools and the agent resolidifies. Thus it can be handled directly without any drying process.

In order to utilize the heated air to maximum advantage, it is recirculated through the system to be used again. More specifically, the warm air flows up into hood 38, suspended beneath plenum chamber housing 36. It is conducted into a recirculating duct 94 (FIGS. 1 and 3), having an outlet 94' into the inlet of fan or blower 46. This partially heated air is then recirculated by fan 46 through duct 34 and through the heater area into heat. The heated flowing air then is forced through the plenum chamber and tubes to the stencil as previously described. The temperature of the air can be controlled with a thermostat sensor and controller 37 operably connected with heat supply 40. The particular selected temperature will vary with the type of printing agent employed. The temperature is that necessary to soften the normally solid agent sufficiently to enable it to pass through the stencil screen orifices under the action of the squeegee.

The illustrated form of the invention is the preferred form. It has been found that this heated gas and air process works excellently with 100% solid printing materials. It achieves high speed stencil printing without drying being necessary. The individual sheets can be stacked one upon another as they are discharged. No scorching of the sheets or materials printed occurs with this assembly. Printing is uniform and of high quality. It is conceivable, however, that certain variations of construction detail may be made in the preferred illustrated form without departing from the concept taught. Hence, the invention is intended to be limited only by the scope of the appended claims and the reasonable equivalents to those defined therein.

I claim:

1. Apparatus for printing with a normally solid, heat fluidizable printing substance comprising: stencil support means; squeegee means operatively adjacent one side of said stencil support means; stock support means operatively adjacent the opposite side of said stencil support means; reciprocating means causing relative movement between said stencil support means and said squeegee means to force a fluid printing substance through a stencil on said stencil support means to a surface on said stock support means; hot gas supply means; and hot gas conduit means from said source means to said stencil support means, and hot gas outlet means at said stencil support means to heat solid printing substance on a stencil on said stencil support means and temporarily render it fluid for printing through the stencil.

2. Apparatus for printing with a normally solid, heat fluidizable printing substance comprising: a supporting framework; reciprocable stencil support means on said framework; squeegee means adjacent one side of said support means and oriented transversely to the direction of reciprocation of said stencil support means to be cooperative therewith; stock support means adjacent said stencil support means on the opposite side thereof of said squeegee means; hot air supply means; hot air distributing means adjacent said stencil support means and mounted to reciprocate therewith to heat solid printing substance applied thereto to a fluid state; and shiftable hot air conveyance means from said hot air supply means to said distributing means.

3. Apparatus for printing with substances that are non-fluid at room temperature and fluid at elevated temperatures, comprising: a supporting framework; generally horizontal stencil support means reciprocably mounted on said framework and adapted to peripherally support a stencil in a plane; squeegee means above and operatively adjacent to said stencil support means, oriented transversely of the direction of reciprocation thereof; stock support means below and operatively adjacent to said stencil support means; hot air source means; an orificed, hot-air distributing, manifold means about said stencil support means, having outlet orifices oriented toward the upper surface of said stencil plane to heat and render fluid a printing substance on the stencil; and hot air propelling and conduit means from said source means to said distributing means.

4. The apparatus in claim 3 wherein said hot air source means includes a plenum chamber spaced above said stencil support means, and said hot air conduit means includes oscillating tubes extending from said plenum chamber to said manifold means.

5. A method of printing with a stencil onto a sheet comprising the steps of: providing a stencil screen and sheet thereunder; distributing onto said stencil screen a normally solid, heat fluidizable printing substance; blowing hot gases across the entire screen and substance thereon from the peripheral portions thereof to temporarily render said substance fluid; passing a squeegee over said screen to force a portion of said substance therethrough onto said sheet to print it; and cooling said printed portion to resolidify it.
